UNITED STATES PATENT OFFICE.

RICHARD E. BEBB, OF CANTON, OHIO, ASSIGNOR TO THE CANTON STAMPING AND ENAMELING COMPANY, OF CANTON, OHIO, A CORPORATION OF OHIO.

CULINARY VESSEL.

1,317,066.

Specification of Letters Patent. Patented Sept. 23, 1919.

Application filed July 13, 1915. Serial No. 39,591.

To all whom it may concern:

Be it known that I, RICHARD E. BEBB, a citizen of the United States, residing at Canton, in the county of Stark and State of 5 Ohio, have invented certain new and useful Improvements in Culinary Vessels, of which the following is a specification.

The invention relates to improvements in 10 culinary vessels, from which it is sometimes, but not always, necessary or desirable to drain liquids from the more solid contents; and the object of the improvement is to detachably secure a segmental screen or shield to the corresponding rim portion of the vessel, for use or removal as may be desired.

A useful form or embodiment of the invention is illustrated in the accompanying drawings forming part hereof, in which—

Figure 1 is a perspective view of a culinary vessel, inverted as for pouring water 20 therefrom, showing the segmental screen in place;

Fig. 2, a cross section of same on lines 2—2, Fig. 1; and

Fig. 3, a detached plan view of the segmental screen.

Similar numerals refer to similar parts throughout the drawings.

The vessel 1 is provided with one or more 30 inwardly presented recesses in one side, at or near the rim thereof, which recesses are for the purpose of engaging corresponding circumferential edge portions of the segmental screen 4 fitted within the rim portion of the vessel and may be in the form of the open slots 3 located slightly below and preferably coplanar with the rim of the vessel.

The screen or shield 4 may be made of 40 perforate, reticulate or impervious metal or material, and as shown is preferably made of resilient sheet metal provided with a sufficient number of perforations 5 for the particular purpose for which it is desired to 45 use the vessel.

The natural resilience of the screen may be supplemented by forming a bead as 6 on its straight or chord edge, and this bead may be further reinforced by providing therein 50 a rod of wire 7 made of spring steel or the like; but the employment of these supplemental means is not essential.

The circumferential edge 8 of the screen

is suitably formed or shaped for fitting the rimmed portion of the vessel when the 55 screen is deflected for engaging the same; and as shown in the drawings, this engagement may be effected by means of the tongues 9 projecting from the edge of the screen. When such tongues are employed 60 or used for this purpose, it is usually sufficient to provide one tongue at the middle of the circumferential edge and one tongue at or near each end thereof.

By these means it is evident that the 65 screen can be readily attached to the vessel by first entering the middle tongue 9 in the corresponding recess 3 of the vessel, and then bending or deflecting the inner middle body portion of the screen upward or downward to permit the end tongues 9 to enter and be engaged in the corresponding recesses 3 in the vessel.

For the purpose of securely engaging the screen with the vessel, and also for 75 arching and crowning its inner middle portion above the plane of its circumferential edge, this edge is cut, shaped or formed on the arc of a circle having a larger diameter than that of the engaging rim portion of 80 the vessel; so that when the screen is secured to the vessel as described, by deflecting the inner portion upward, the same is held by the abutment of its end portions with the sides of the vessel, from resuming a flat 85 position, and the inner middle portion of the screen is thus maintained in an upwardly arched or crowned position, as shown more clearly in Fig. 2.

To those skilled in the art of making 90 cooking vessels, many alterations in construction and differing embodiments and applications of the invention will suggest themselves, without departing from the spirit and scope thereof; the disclosure and the 95 description herein being purely illustrative and are not intended to be in any sense limiting.

I claim:

1. A culinary vessel having inwardly presented recesses in the rim portion of one side, and a resilient segmental screen having its circumferential edge curved on a larger diameter than the rim of the vessel, and deformed to engage in the recesses by deflection of the body portion of the screen. 100 105

2. A culinary vessel having inwardly presented recesses in the rim portion of one side, and a resilient segmental screen having tongues on its circumferential edge for engaging in said recesses by a deflection of the body portion of the screen.
3. A culinary vessel having inwardly presented recesses in the rim portion of one side and a resilient segmental screen having 10 its circumferential edge formed to engage in said recesses by a deflection of the body portion of the screen.
4. A culinary vessel having inwardly presented recesses in the rim portion of one side, and a segmental screen having a circumferential edge formed to engage in said recesses by a deflection of the body portion of the screen and having a resilient reinforcement along its chord edge.
- 20 5. A combination of a culinary vessel and a resilient screen, there being interengaging means between the circumferential edge of the screen and the inner side of the rim portion of the vessel for detachably engag-

ing the parts together by a deflection of the 25 body portion of the screen.

6. The combination of a culinary vessel and a resilient segmental screen, there being interengaging means between the circumferential edge of the screen and the inner 30 side of the rim portion of the vessel for detachably securing the parts together and arching the body portion of the screen by a deflection thereof.

7. The combination of a culinary vessel 35 and a resilient segmental screen having its circumferential edge normally curved on a larger diameter than the rim of the vessel, there being interengaging means between said edge and rim, for securing the screen to 40 the vessel and arching its body portion by the abutment of its end portions with the sides of the vessel.

R. E. BEBB.
